UNITED STATES PATENT OFFICE.

PHILEMON O. DICKINSON, OF NEWARK, NEW JERSEY.

DESIGN FOR A LID FOR BOXES, &c.

SPECIFICATION forming part of Design No. 25,240, dated March 10, 1896.

Application filed October 30, 1895. Serial No. 567,456. Term of patent 3½ years.

To all whom it may concern:

Be it known that I, PHILEMON O. DICKINSON, a citizen of the United States, residing at Newark, in the county of Essex and State of New Jersey, have invented and produced a new and original Design for Lids for Boxes, of which the following is a description, reference being had to the accompanying drawing, which illustrates the design.

10 The drawing shows a representation of a box-lid ornamented with my design.

The design consists of the side or lid of a box of substantially rectangular shape bearing the ornamental border A located slightly

within the profile of the lid or side, and the 15 shield-like figure B composed of inverse and reverse scrolls embellished with representations of conventionalized leaves surrounding the plain panel surface C, the general style of the whole design being of the rococo order. 20

What is claimed as new is—

The design for the lid of a box, or similar article, as herein described and shown.

PHILEMON O. DICKINSON.
